CLOTHESPIN OR THE LIKE

John Ditto, Herrin, Ill., assignor of one-fourth
to Collins Brown and one-fourth to C. E.
Duncan, both of Herrin, Ill.

Application November 12, 1936, Serial No. 110,534

1 Claim. (Cl. 24—261)

My invention relates generally to spring clasps or clamps, and particularly to a spring clothes pin, and an important object of my invention is to provide an efficient and rugged device of this 5 character which is easily operated and is serviceable, and which can be constructed of one piece of wire if desired.

Another important object of my invention is to provide a clothes pin or the like of the character indicated which is constructed throughout 10 of spring material, so as to afford the maximum of spring clamping action for its size and weight.

Other important objects of my invention will 15 be apparent from a reading of the following description taken in connection with the drawing, wherein for purposes of illustration I have shown a preferred embodiment of my invention.

In the drawing:—

Figure 1 is a general side elevational view of 20 an embodiment of my invention.

Figure 2 is an end elevational view.

Figure 3 is a perspective view.

Figure 4 is a horizontal sectional view taken 25 approximately on the line 4—4 of Figure 1 and looking downwardly in the direction of the arrow.

Referring in detail to the drawing, the numeral 5 generally designates the embodiment and this may be constructed of a single length of wire which is bent beginning at one end, at 30 the point 6 and again at the point 7 to provide a closed loop that acts as confining member for the legs to be described, the bend at the point 7 being laterally inwardly and then outwardly and upwardly at an acute angle to provide the arm 35 8 which has a counterpart 9 joined by a bight portion 10. The lower end of the arm 9 is extended downwardly into a slightly bowed portion 10 and below this into a U-shaped leg or clamp member 11 composed of the legs 12 and 13. The upper part of the leg 13 is bowed as 40 indicated by the numeral 14 like the part 10 and above this has the straight part 15 which has a counterpart 16 joined by a bight 17 at the upper end thereof. As clearly shown in the 45 drawing the upper part 15 of the leg 13 passes through and is enclosed by the retaining member formed by the bends 6 and 7. A second retaining member formed by bending the opposite end of the single length of wire is formed into 50 a loop by the bends 18 and 19, which is oppositely disposed relative to, but corresponding in form and position to the loop made by the bends 6 and 7, the bend 19 resulting in the straight arm 20 which has a counterpart 21 joined to the arm 55 20 by the straight bight 22. The lower end of the arm 21 is angularly bent at the point 23 and below this has a slight bow 24 opposite to the bow 14, and below the bow 24 merges into the bow 14, and below the bow 24 merges into the straight leg 25 which has a counterpart 26.

The last has at its upper end a bow 27 and opposed to the bow 10 in the leg 12, the bow 27 having its upper part passing through the retainer formed by the bends 18 and 19 joining the arm 16. The lower ends of the legs 25 and 26 are joined by a curved bight 28 corresponding to the curved bight 11. By this arrangement the legs 13 and 25 and 12 and 26 are opposed and held in spring-pressed engagement while the finger grips provided by the legs 9 and 8 and 20 and 21 and their respective bights 10, 22 outwardly spread away from each other and away from the center member which is provided by the arms 16 and 15 and the bight 17 as clearly shown in Figure 3. By pressing the finger grips toward each other, the clamp members may be separated to engage the clothes or other objects. Upon releasing the finger grips the clamp members will strongly and securely clamp the clothes or the like. The length of the center member formed by legs 15, 16 and bight 17 is substantially equal in length to the length of the gripping members.

Although I have shown and described herein a preferred embodiment of my invention, it is to be definitely understood that I do not desire to limit the application of the invention thereto, and any change or changes may be made in the materials and in the structure and arrangement of the parts, within the spirit of the invention and the scope of the subjoined claim.

What is claimed is:—

In a one piece clothespin structure, a pair of eye members, spaced apart laterally upon opposite sides of the structure in the approximate center thereof, a pair of opposed U-shaped hand grips on one side of said center normally divergent and comprising a pair of side legs, respectively, and a pair of opposed U-shaped clamping jaws on the other side of said center adapted for relative separative movement by movement of said hand grips together and also comprising a pair of side legs, respectively, one leg of each hand grip extending from an eye member on one side of the structure and the other leg of each hand grip extending into the eye member on the opposite side of said structure and merging at an angle into one of the legs of one of the clamping jaws whereby said merging leg and the related jaw leg are fulcrumed in the related eye member, the other leg of each jaw having an extension projecting through the eye member on the related side of the structure to the hand grip end of the latter, said extension being connected at their extremities and reacting together with the legs of said jaws to oppose separative movement of the latter.

JOHN DITTO.
